UNITED STATES PATENT OFFICE

162,131

AUTOMOBILE TIRE

Loyd O. Dodson, Los Angeles, Calif., assignor to Vogue Rubber Company, Chicago, Ill., a corporation of Illinois

Application April 1, 1949, Serial No. 1,763

Term of patent 7 years

(Cl. D90—20)

To all whom it may concern:

Be it known that I, Loyd O. Dodson, a citizen of the United States, residing at 115 So. McCadden Pl., Los Angeles, in the county of Los Angeles and State of California, have invented a new, original, and ornamental Design for an Automobile Tire, of which the following is a specification, reference being had to the accompanying drawing, forming a part thereof.

In the drawing:

I claim:

The ornamental design for an automobile tire, as shown.

LOYD O. DODSON.
